Howson & Howson

UNITED STATES PATENT OFFICE.

ROBERT RENKE, OF PHILADELPHIA, PENNSYLVANIA, ASSIGNOR TO LEWIS AND ROTH CORPORATION, OF PHILADELPHIA, PENNSYLVANIA, A CORPORATION OF PENNSYLVANIA.

HIGH-VOLTAGE AIR-BREAK SWITCH.

1,415,708.

Specification of Letters Patent.

Patented May 9, 1922.

Application filed June 25, 1919. Serial No. 306,629.

To all whom it may concern:

Be it known that I, ROBERT RENKE, a citizen of Russia, having declared my intention of becoming a citizen of the United States, 5 residing in Philadelphia, Pennsylvania, have invented High-Voltage Air-Break Switches, of which the following is a specification.

One object of my invention is to provide a switch particularly designed for breaking 10 high voltage currents in air, for which purpose its construction is primarily such as to avoid the production of injurious mechanical stresses under conditions of operation, particularly in its insulating elements.

15 It is further desired to provide a switch of the above noted type with a novel arrangement of auxiliary contacts or horns particularly designed to maintain the arc formed on opening said switch, at a constant length while drawing it away from 20 the main contacts and finally to cause its breakage when said horns are moving at a relatively high speed.

My invention further contemplates a high 25 voltage switch in which the parts are so arranged and constructed that the contacts cannot open or close under the action of gravity in the event of the breakage or accidental disconnection of the operating gear 30 but will under all conditions tend to remain in their open or closed condition as the case may be.

Another object of my invention is to provide a high voltage switch having both of 35 its cooperating contacts movable and operative in the arcs of circles, their relative positions being such as to cause the formation of a short arc immediately after their separation and its subsequent maintenance at a 40 substantially constant length while it is drawn away from the vicinity of said main contacts to the extremities of auxiliary contacts or horns, where it is suddenly broken by the separation of these latter at a high 45 speed.

The invention further contemplates a 50 switch having the above noted characteristics, which in addition to being substantial, shall be of such construction as to not easily 55 get out of order and in which the mechanical stresses on the insulators and operating gear shall be materially less than has hitherto been the case in similar switches.

These objects and other advantageous 60 ends I attain as hereinafter set forth, refer-

ence being had to the accompanying drawings, in which,

Fig. 1 is a side elevation of a switch constructed in accordance with my invention;

Fig. 2 is an end elevation of the switch 60 shown in Fig. 1;

Fig. 3 is an enlarged transverse section through the main contacts;

Figs. 4 and 6 are perspective views respectively of one of the contact heads and 65 its main contact; and

Fig. 5 is a transverse section of one of the connecting lugs and its associated conductor.

In the above drawings 1 represents a relatively fixed supporting structure, in the 70 present instance consisting of a suitable length of a channel section mounted in any desired manner and having attached to either or both of its ends one end of a series of strain insulators 2 to whose opposite end 75 is attached a terminal fixture 3 of a high voltage line 4. Obviously the end of a second line may be similarly attached to the opposite end of the channel section 1 which has fixed to and projecting from its upper 80 face a pair of bearings 5 each rotatably supporting a short shaft 6. Said bearings are preferably of the double or forked type and between their arms each shaft has fixed to it an upwardly projecting arm 7 on which is 85 mounted a suitable high voltage insulator 8.

Suitably mounted on and fixed to the top of each of these insulators is a metal frame to which is bolted or otherwise connected a head 9 having a flat base 25 and a hollow 90 cylindrical body 11 formed with a laterally projecting lug 13. Screwed or otherwise mounted in the body 11 which extends from one side of the base, is an elongated metal rod 12 constituting a horn or auxiliary contact while said body has removably though rigidly mounted on it a main contact 10 in the form of a split sleeve 26 and an integral contact plate 10. This latter is so formed and supported that its plane includes or is 100 substantially parallel with the longitudinal axis of its insulator 8 and head 9; the arrangement being such that each contact has a flat face positioned to electrically engage and be substantially concentric with the similar face of the other contact when the switch is closed. The sleeves of the contact plates frictionally and removably grip the bodies 11 of the respective heads and the proximal portions of the edges of the con- 110

tacts 10 are bevelled or inclined to insure the engagement of their flat faces when the members of the switch are moved toward their closed positions.

- 5 Each of the lugs 13 has pivoted to it one end 14^a of a rigid, relatively stiff conducting rod 14 whose second end has sweated or otherwise fixed to it a terminal 15 connected through a flexible conductor 16 with 10 the terminal fixture 3. This latter is so constructed that the flexible conductor is removably clamped to it and it also has clamped upon it a fulcrum plate 17 to which is pivoted one end of a strut 18 whose opposite end is pivoted to the terminal 15 on the outer end of the rod 14. Each of the shafts 6 is extended at one end beyond its bearing 5 and has fixed to this extension an arm 19; these two arms extending toward 15 each other and, in the present instance, at an angle of slightly more than 90° to the arms 7 on their respective shafts.

Suitably fixed to one side of the supporting base 1 is a downwardly projecting yoke 25 structure 20 constituting a guide for a vertically reciprocable operating member 21 having a laterally projecting head 22 whose ends are connected by links 23 to the ends of the arms 19 respectively. Any desired device 30 may be provided for moving the operating rod 21 up or down and as typical of this, I have shown an operating handle 24 fixed to one end of a shaft or spindle 25 mounted in a bearing 26 attached to a wall 35 or other supporting structure 27. Also fixed to the shaft or spindle 25 is a short arm 28 to which is pivoted the lower end of the arm 21.

With the above described arrangement of 40 parts, when the operating handle 24 is in its lower position shown, the two arms 7 with their insulators 8 are inclined toward each other and their heads 9 are so designed and mounted that when the rod 21 occupies 45 its lowest possible position with the head 22 engaging the yoke 20, the two flat faces of the contacts 10 are in engagement. Current is then free to flow from the line 4 to the conductor 16, rod, 14, through the two 50 heads 9, to the second of the rods 14, through the second flexible conductor 16 attached thereto and thence to the second line or to any apparatus or device to which the conductor 16 may be connected.

55 If now the operating handle 24 be swung upwardly through an arc of approximately 180°, the operating rod 21 is moved upwardly, and through the links 23 and arms 19, the shafts 6 are turned through an angle 60 of about 90°. At the beginning of this movement the two contacts 10 are moved apart, with the result that an arc is struck or formed between the nearest portions of their adjacent upper edges. Since as shown 65 in Fig. 2 the horns 12 lie and move in par-

allel planes, as the distance between the contacts 10 is increased, the arc moves from the latter to the lower ends of said horns, and as these swing about the shafts 6 as axes, while the distance between them remains constant, the arc moves upwardly upon them in an endeavor to avoid an increase in its length, as well as under the action of the upwardly moving body of hot gas produced. Finally however when the 75 shafts 6 and said horns are being moved at their maximum velocity under the action of the operating handle 24, the arc reaches the ends of said horns and as the continued movement of the latter separates these ends 80 at a high velocity, the arc is drawn out to its limit of length and is quickly broken, the horns and their associated parts ultimately coming to rest in the widely separated positions indicated in dotted lines in 85 Fig. 1.

With this method of operation and construction of parts it will be noted that the weight of the arms 7, insulators 8, head 9 and horns 12 is so disposed relatively to the 90 pivot shafts 6 that when the switch has once been opened, said parts tend to remain in their open or separated positions under the action of gravity, and similarly when the operating handle 24 is swung downwardly into the position shown, the several parts are moved from the positions indicated in dotted lines and after passing through dead points, tend to move under the action of gravity into the positions illustrated in Fig. 1, in which the contacts 10 are in engagement and the circuit through the switch is complete.

One important feature of my invention resides in the disposal of the parts in such 105 a manner that the mechanical stresses in the switch elements due to their operation under working conditions are practically negligible, for the insulators particularly are so supported and related to the switch contacts 110 that they are free from torsional and lateral stresses. In addition to the fact that the horns 12 do not engage each other, it is noted that their arrangement and movement is such that the arc is broken from their tips 115 or extremities at the time when these are moving apart at a maximum velocity.

On closing the switch, the circuit is completed not through the horns but directly 120 through the plates 10, which owing to their inclined or wedge shaped edges necessarily ride one upon the other when the switch is closed and make good electrical contact. The horns may be easily removed and replaced whenever this is desirable and if for 125 any reason the operating mechanism of the switch should become disconnected from the shafts 6, there would be no resulting movement or operation of the arms 7 or of the contact members 10 carried thereby, since 130

as above pointed out, the switch elements tend to remain in their open or closed positions as the case may be.

By the use of the stiff conducting rods 14 and the supporting struts 18, any possible interference of the flexible conductors 16 with the main switch members or their associated parts is effectually prevented, since said rods and struts insure said conductors 10 being held away from their respective insulators 8 as well as from the horns and contact plates associated therewith.

I claim:

1. The combination in a high voltage switch of two pivotally mounted cooperative contacts; means for simultaneously swinging said contacts on their pivots to cause them to engage or disengage each other; with horns respectively carried by 20 said contacts and movable therewith in parallel planes spaced apart to maintain an arc gap of substantially constant length after the contacts have been separated, until the ends of said horns begin to separate.

2. The combination in a high voltage switch of two pivotally mounted cooperative contacts; means for simultaneously swinging said contacts on their pivots to cause them to engage or disengage each 30 other; with rigid, permanently disengaged horns respectively carried by said contacts and positioned to move in substantially parallel planes when the contacts are moved.

3. The combination in a high voltage switch of a supporting structure; two arms pivotally mounted thereon; contacts carried by the arms respectively; means for insulating said contacts from their respective arms; substantially straight, rigid horns associated 40 with the contacts respectively and positioned one across but spaced away from the other when the switch is closed, and movable in parallel planes when the arms are turned on their pivots; with means for simultaneously moving said arms to cause the contacts to engage or disengage each other.

4. The combination in a high voltage switch of two movably supported cooperative contacts; horns respectively associated 50 with said contacts and positioned to maintain an arc gap of constant length as the contacts are separated until the extremities of the horns have been brought immediately adjacent each other and thereafter move said 55 extremities apart; with means for operating the switch.

5. The combination in a high voltage switch of a supporting structure; two contacts movably mounted on but insulated 60 from said structure and from each other; two substantially straight rods respectively connected to the contacts and extending adjacent but permanently disengaged from each other; with means for simultaneously 65 moving both of said contacts into and out

of engagement with each other and thereby causing said rods to move in substantially parallel planes, the rods being positioned so that their outer extremities first approach each other and then move apart as the switch 70 is opened.

6. The combination in a high voltage switch of a supporting structure; two arms pivotally mounted thereon and each free to move from one side to the other of a 75 neutral position; contacts respectively carried by said arms in positions to engage each other when the arms occupy predetermined positions on the adjacent sides of their respective neutral positions; horns carried 80 by said arms and extending adjacent each other in parallel separated planes when said contacts are in engagement; with means for simultaneously swinging the arms on their pivots to move the contacts to the opposite 85 sides of their neutral positions and at the same time separate the extremities of the horns after moving them adjacent each other in their planes.

7. The combination in a high voltage 90 switch of a supporting structure; arms movably mounted on said structure; contact plates having oppositely facing substantially flat coacting surfaces and respectively carried by but insulated from said arms; means for simultaneously moving both of said arms to cause engagement or disengagement of 95 said plates; and horns respectively projecting from relatively distant portions of the contact plates and movable therewith in adjacent permanently separated parallel planes.

8. The combination in a high voltage switch of a supporting structure; arms movably mounted on said structure; contact plates having substantially flat oppositely 105 facing coacting surfaces and respectively carried by but insulated from said arms; means for simultaneously moving both of said arms to cause engagement or disengagement of 110 said plates; and permanently separated horns respectively associated with the contact plates and movable therewith in adjacent parallel planes, each of said arms and its associated parts being mounted on its supporting structure in position to tend to 115 move from a neutral position into either of two extreme positions in one of which the contacts are in engagement.

9. The combination in a high voltage switch of a supporting structure; two arms pivotally mounted on said structure and extending toward each other; two other arms respectively in rigid connection with the first arms and respectively movable thereby into either of two positions on opposite sides 120 of a neutral position; two cooperative contacts respectively carried by but insulated from the second pair of arms; horns associated with the contacts and movable therewith in substantially parallel separated 125 130

- planes; current conductors connected to said contacts respectively; and mechanism associated with the first pair of arms for moving the contacts into and out of engagement with each other.
10. The combination of a supporting structure; two bearings mounted thereon; two substantially parallel shafts carried by said bearings; a pair of angularly disposed arms fixed to each of said shafts; a set of high tension insulators mounted on one of the arms of each set; coating contact plates mounted on the insulators; horns connected to said contact plates and movable therewith in substantially parallel separated planes; current conductors connected to the contacts; and operating mechanism connected to the second arm of each pair for moving the other
- 15 arms with their associated parts from one side to the other of neutral positions to bring the contacts into or out of engagement with each other.
11. The combination in a high voltage switch of a supporting structure; two arms pivotally mounted thereon; high tension insulators respectively carried by said arms; heads each having a contact plate respectively carried by said insulators; horns carried by said heads and movable with the contacts in substantially parallel separated planes; means for simultaneously swinging said arms with their associated parts on their pivots; and current conductors respectively connected to said heads.

In witness whereof I affix my signature.
ROBERT RENKE.
